LIPSTICK CASE

Sophie Frydlender, Paris, France, assignor to
Lancome Societe Anonyme, Paris, France, a corporation of France

Application May 15, 1945, Serial No. 593,805
In France January 29, 1944

Section 1, Public Law 690, August 8, 1946
Patent expires January 29, 1964

2. Claims. (Cl. 206—56)

1.

The present invention relates to a lip-stick case of the known kind in which the driving in and out of the stick-holder socket is controlled by the rotation of a device provided with a helical groove. The object of the invention is to provide a lip-stick case of this kind easy to manufacture, easy to handle and the user of which does not risk to lose the various elements and more particularly the movable closing cap.

For this purpose, the lip-stick case according to the invention is essentially characterized by the fact that the closing cap is established so as to be able to fit the lower part of the rotary device provided with a helical groove, the said lower part being almost entirely concealed inside the body of the case so that its rotation must be controlled through the medium of the closing cap.

In these conditions, in order to drive out the stick-holder socket the user is obliged to fix the closing cap upon the lower part of the control device and he must leave the said cap secured to said lower part to drive back the socket into the case after use. Thus, he has only one piece in hand during the whole working of the case and, accordingly, cannot lose the cap.

Further characteristic features of the invention will appear from the complementary description given hereunder with reference to the appended drawing, which shows, by way of non-limitative example, a form of execution of the lip-stick case which forms the subject matter of this invention. In the said drawing:

Figure 1 is a perspective view of the case in the closing position.

Figures 2, 3 and 4 are also perspective views of the various elements of the case.

Figures 5 and 6 are partial sectional views of the case showing the interlocking device for the closing cap and the fixation of the control device provided with a helical groove respectively.

Figure 7 is a perspective view of the case in the working position, and

Figure 8 is a vertical cross sectional view of the lip stick case shown in Figures 1 to 7 and illustrating a suitable form of ejection and retraction mechanism.

In the example shown the body 1 of the case has a cylindrical shape. It is closed by a cap 2 shaped, for instance, as a dome surmounted by

a frusto-conical extension so that it may be taken and handled more easily. Near its lower edge the cap 2 (Figure 2) is provided with a groove 3 intended for insuring its fixation in the closing position as will be explained later on.

Inside the case 1 is located the cylindrical cover 4 of the device provided with a helical groove which determines the displacements of the socket carrying the lip-stick 5. The inner construction of such a device is well known and will not be described particularly here. According to one of the particularities of the invention the fixation and the centering of the cover 4 in the body 1 of the case are insured by means of an intermediary jacket 6 forced into the body 1 and fitting the inner surface of the latter. Said jacket (see Figure 3) is provided on its upper part with three female teats or humps chased in its thickness and engaged by three corresponding male teats or seats 8 formed on the wall of the cover 4 (Figure 6). Three other female teats 9 similar to the preceding ones are provided for about the lower part of the jacket 6 and contribute to the centering of the cover 4. In order to allow the mounting of the helical device into the jacket and the engagement of the male teats 8 into the female teats 7, the said jacket is slit on its whole length, both edges 10a, 10b of the said slot (Figure 3) being provided with complementary interhooking elements exactly fitting one another in order to avoid any shifting of the basic curves of the jacket. The disassembling of the device can be effected by inserting between the cover 4 and the jacket 6 a socket comprising three bayonet notches spaced from another by distances corresponding to those of the centering teats 9 and coming into contact with the latter which they then enclose; one then only has to exert a pull on said socket to bring the whole device out of the body of the case.

On its upper edge the jacket 6 is, furthermore, provided with slots extending along generatrices and forming three elastic blades 11 respectively showing, about at half-length, a projection 12 extending inwardly. The projections 12 lie on the same circumference and are disposed so that they yield when the lower edge of the cap engages the case and then engage the groove 3 of the said cap under the thrust of the blades

if which carry them, thus locking the said cap in the closing position (Figure 5).

The rotary bottom 13 serving in the usual manner to control the working of the device provided with a helical groove has a diameter which is slightly greater than that of the cover 4 of the device and it projects only very slightly on the lower part of the case 1, as may be seen from Figure 1. The said bottom offers a slight conicity extending downwards and to which corresponds a conical bore 14 provided on the lower edge of the cap 2 so that the latter can fit the said bottom as shown in chain dotted lines in the lower part of Figure 6, without exceeding the height of the said bottom.

The whole working of the so formed case clearly results from the above given explanations. In order to use the lip-stick one pulls the cap 2 closing the case so as to set free the opening of the latter; the cap is then fitted into the clearance surrounding the bottom member 13 and onto the bottom 13 and one twists it like a fountain-pen, this latter operation causing the lip-stick 5 to project up to the desired height (Figure 7). After use the cap is rotated in the reverse direction in order to drive back the lip-stick wherewithal it is removed from the bottom 13 and replaced on the opening of the case 1 by pushing till the projections 12 of the elastic lugs 11 engage the groove 3.

Any suitable known kind of device for effecting ejection and retraction of the lip stick may be provided, for example, the cover or sleeve 4 may house a helical groove mechanism as shown in Figure 8. This mechanism comprises a stick carrier or socket 4c which fits telescopically in a tube 4b which is press-fitted on the bottom member 13. The stick carrier 4c is provided with a stud or claw 15 operable in a longitudinal groove 16 in the tube 4b. The stud 15 also extends into a helical groove 17 in a tube 4a press-fitted in the cover sleeve 4, previously referred to. Sleeve 4 is provided with three teats or humps 8 in its top quarter and envelops or covers the helical groove device.

The jacket 6 shown in Figure 3 is slotted along its entire length at 10a and 10b to enable it to be force-fitted within the body 1. The jacket is provided in its top quarter with three seats 7 adapted to receive the three humps 8 on the cover 4, for retaining the latter releasably inside the body 1. The jacket is slotted lengthwise intermediate the seats 7 to provide the three spring tongues or blades 11 each of which has a projection 12 as previously stated. The projections 12 are adapted to snap into the groove 3 of the cap 2 for locking the cap in closed position.

In operation, after the cap 2 is removed to open the upper end of the case, the cap is plugged from below on to the bottom member 13 and is turned by finger grip on the frusto-conical extension. When the parts 2, 13, and 4b are turned

as a unit inside the structure formed by the parts 1, 6, 4, and 4a, the longitudinal slot 16 is displaced parallel to itself so as to rotate the pin 15 about the axis of the tube 4a. The helical groove 17 in the tube 4a which is fixed thereby causes the stud 15 and stick holder 4c to move longitudinally so as to project the stick from the case.

After use, the cap 2 is turned reversely while still on the bottom member 13 to retract the stick holder. Then the cap is removed from the bottom member 13 and is restored to its closing position as shown in Figure 5, the projections 12 of the spring blades 11 engaging the cap groove 3 for retaining the cap in closed position.

What I claim is:

1. In a lip stick case, a body open at its upper end through which a lip stick housed within the case can be projected; a cap for closing said open upper end of said body and having a lower edge portion of generally annular cross section having an uninterrupted smooth inner surface; a bottom member housed within said body and being rotatable therein for effecting projecting of the lip stick through the open upper end of said body, the outer surface of said bottom member being uninterruptedly smooth and complementary to said inner surface of said cap, and there being a clearance around said bottom member and the inside of said body, said cap lower edge portion being of a size to be extended freely within said body by being moved axially with respect to said case and to fit over and closely and frictionally embrace said bottom member outer surface irrespective of the relative angular positions of said bottom member and said cap with reference to the axis of said case, to thereby effect a frictional rotation-transmitting driving connection between said cap and said bottom member.

2. A lip stick case as set forth in claim 1 in which the complementary outer surface of the bottom member and inner surface of the cap are of correspondingly conical shapes.

SOPHIE FRYDLENDER.
